REVOLVING CASE FOR CLINIC THERMOMETERS
FOR ZERO SETTING THE SCALE THEREOF

Piero Catelli, Como, Italy (% Dr. Ing. Misitano A.G.,
Via Padova 217, 20127 Milan, Italy)

Filed Nov. 13, 1968, Ser. No. 14,494

Term of patent 14 years

Int. Cl. D10—09

U.S. Cl. D52—7

FIG.3

FIG.1

FIG.2

FIG. 1 is a side elevational view of a revolving case for clinic thermometers for zero setting the scale thereof, showing my new design;

FIG. 2 is a view of the right side of FIG. 1; and

FIG. 3 is a view opposite to that of FIG. 2.

I claim:

The ornamental design for a revolving case for clinic thermometers for zero setting the scale thereof, as shown.
